UNITED STATES PATENT OFFICE.

JOHN SORENSEN, OF RHINELANDER, WISCONSIN.

SETTING DEVICE FOR RESAWING MACHINES.

Application filed August 9, 1920. Serial No. 402,184.

To all whom it may concern:

Be it known that I, JOHN SORENSEN, a citizen of the United States, residing at Rhinelander, county of Oneida, and State 5 of Wisconsin, have invented new and useful Improvements in Setting Devices for Resawing Machines, of which the following is a specification.

My invention relates to improvements in 10 setting devices for resawing machines.

The object of my invention is to provide improved means for locking the table adjusting lever in its desired positions of adjustment. More particularly stated, the object of this invention is to provide the table 15 adjusting lever with a plurality of locking devices and associated toothed or notched segments, and arranging the locking devices and segments in such a manner as to not only avoid confusion in setting the lever in the proper position, but also to facilitate the making of nice adjustments of the lever at points which lie between the adjustments which are permissible in the use of a single 20 locking device and segment.

In my improved construction it is possible to lock the lever in one position of adjustment for cutting boards of a given thickness from slabs of soft wood, and to 25 subsequently utilize the same machine for cutting boards from hard wood slabs by simply substituting saws, and slightly readjusting the lever to allow for the difference in the widths of the kerfs made by 30 saws which are employed for sawing hard wood, as distinguished from those which are employed for sawing soft wood. It is well known that saws for sawing soft wood must have a wider set than those which are employed for cutting hard wood. By providing 35 one set of locking devices for holding the lever in a proper position for sawing hard wood boards of predetermined thickness, and another set of locking devices for holding the lever in a proper position for 40 sawing soft wood boards, it becomes possible to not only secure minute variations in adjustment, without difficulty, but it also becomes possible for inexperienced workmen to make the necessary changes in adjustment, without danger of error or confusion.

In the drawings:—

Figure 1 is a fragmentary view in side 45 elevation of those portions of a resawing machine essential to be illustrated for the

purpose of disclosing my invention, and its mode of operation, my invention being embodied in the machine as illustrated.

Figure 2 is a front elevation of the parts 60 illustrated in Figure 1.

Figure 3 is a plan view, the saw being partially broken away above the table adjusting lever.

Like parts are identified by the same 65 reference characters throughout the several views.

The table adjusting lever 1 is pivotally fulcrumed at 2 to a frame member 3. The general function of this lever is to support and adjust a vertically movable table or slide 5, said table being raised or lowered by a cross lever 6 connected with the lever 1 by a link 7 pivoted to the lever 1 at 8. These parts may be of any ordinary construction. They are more fully shown and described in a companion application executed by me bearing even date herewith, and which shows and describes means for actuating the lever 1 from a suitable source 75 of mechanical power through the vertically movable bar 8.

But it may be assumed for the purpose of the invention herein disclosed, that the lever 1 may be swung in a vertical plane 85 upon its pivotal fulcrum 2, either through mechanical power or through manual manipulation.

It will be observed that the machine frame is provided with a pair of notched 90 segments or arcuate bars 10 and 11, between which the long arm of the lever 1 extends. The outer end of this arm is preferably reduced and extended to form a handle, or handle portion 12, whereby the lever may be 95 manually raised or lowered. A locking slide 13 is mounted in a suitable housing or bracket 14, on one side of the handle portion 12 of the lever, and the inner end of this slide is adapted to engage in any one 100 of the notches 15 formed in the outer margin of the arcuate bar or segment 10. A coiled spring 16 is interposed between a shoulder or projection 17 on the slide 13, and the outer wall of the casing 14. The 105 spring 16 is a compression spring, and tends to automatically push the slide 13 into any notch with which it may be in registry, but the pin or slide may be retracted to withdraw it from the notch by means of 110 the small hand lever 17^a pivoted to the housing 14 at 18 to the slide 13 at 19.

The opposite side of the handle portion 12 is provided with a similar housing or an extension of the housing 14, in which a spring actuated slide 22 is mounted, this slide being retracted by means of the small hand lever 32, connected and operating in the same manner as the lever 17. The slide 22, however, is adapted to engage in the notches 24 of the arcuate bar 11.

10 The notches 15 in the arcuate bar 10 may be assumed to be disposed with reference to the desired adjustments of the table 5 for sawing boards of standard thickness from soft wood, and the notches 24 in the bar or 15 segment 11 may correspondingly be assumed to be disposed in accordance with the requirements for sawing standard hard wood boards. Therefore, by retracting both of the hand levers 17^a and 32, lever 1 may 20 be raised or lowered and adjusted into substantially the desired position for sawing boards of a given thickness, as indicated by suitable gage marks on the segments or bars 10 and 11. Thereupon, both levers 17^a and 25 32 are released, and if soft wood boards are to be sawed, the table adjusting lever 1 will then be moved until its locking slide 13 engages in the proper notch in segment bar 10. If hard wood boards are to be sawed, 30 the lever 1 will be manipulated until the locking slide 22 engages the proper notch 24 in the other segment bar 11. It will not even be necessary for the operator to inspect the slides 13 and 22, for the reason that the 35 levers 17^a and 32 indicate by their relative positions which of the locking slides is in locking position. The levers 17^a and 32 are in sufficiently close proximity to each other to enable the operator to simultaneously 40 grasp both of them with one hand, using the other hand to manipulate the lever 1, when manual operation of that lever is required.

If the lever 1 is operated by mechanical power, the operator will still manipulate the two levers 17^a and 32 with one hand, and use the other to control the power connections.

For the benefit of inexperienced workmen,

the levers or slide actuating members 17^a and 32 may be suitably marked to identify or designate their purpose. For example, the lever 17^a may be marked with the letter "S" to indicate its use for locking the table adjusting lever in position for soft wood 55 operations. The other lever may be marked with the letter "H" to indicate its use for hard wood adjustments. Both may be held retracted by latch dogs 26.

It will be understood that my invention 60 has been illustrated and explained as used in connection with a band saw 27, which runs in the form of an endless belt over the table 5, and in the path of the work, the latter being moved across the table at right 65 angles to the line along which the saw travels.

I claim:

1. The combination with the table adjusting lever of a resawing machine, of a 70 plurality of locking devices for said lever, one of said locking devices being adapted to hold the lever in various positions for sawing boards of standard thicknesses from 75 soft wood, and another of said locking devices being adapted to hold the lever in various positions for sawing boards of standard thicknesses from hard wood.

2. The combination with a table adjusting lever for a resawing machine, of a set of 80 locking slides mounted upon said lever, a slide operating member associated with each slide, and a notched segmental member associated with each slide and adapted to receive said slide within the notches thereof 85 to lock the lever in adjusted position, the notches within said segmental members being spaced different distances apart in the respective members corresponding to the differences existing between saw cuts for 90 soft wood and for hard wood.

In testimony whereof I affix my signature in the presence of two witnesses.

JOHN SORENSEN.
